US0D1039263S

(12) **United States Design Patent** (10) **Patent No.:** **US D1,039,263 S**
(45) **Date of Patent:** **** Aug. 20, 2024**

(54) **UMBRELLA FRAME**

(71) Applicant: **Yotrio Group Co., Ltd.**, Zhejiang (CN)

(72) Inventors: **Yong Hu**, Zhejiang (CN); **Jianqiang Xie**, Zhejiang (CN)

(73) Assignee: **Zhejiang Yotrio Group Co., Ltd.**, Zhejiang (CN)

(**) Term: **15 Years**

(21) Appl. No.: **29/858,779**

(22) Filed: **Nov. 3, 2022**

(51) LOC (14) Cl. **03-03**

(52) U.S. Cl.

USPC **D3/10**

(57) **CLAIM**

The ornamental design for umbrella frame, as shown and described.

DESCRIPTION

FIG. 1 is a perspective view of an embodiment of the umbrella frame incorporating the new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines depict parts of an umbrella frame that form no part of the claimed design.

1 Claim, 7 Drawing Sheets
